UNITED STATES PATENT OFFICE

2,455,809

PACKAGE AND CABINET FOR
FROZEN FOODS

Milton Rifkin, Denver, Colo., assignor, by mesne assignments, to Frez-O-Mat Corporation, a corporation of Illinois

Application March 7, 1944, Serial No. 525,461

3 Claims. (Cl. 312—36)

1

This invention relates to a frozen food package and cabinet therefor. Frozen foods are usually packed in cardboard boxes or cartons and these boxes must be continually stored in refrigerated cases. The usual custom is to place them in refrigerated cases having hinged top lids. This method is unsatisfactory since the cartons are not on display to entice purchasers and the continual opening of the lids and handling of the contents therein in order to reach and remove the desired cartons results in great refrigeration loss and damaged goods.

The principal object of this invention is to provide a package for frozen foods and a refrigerated display case for the foods, which will display the package in full view of the purchaser; which will allow removing of any desired package without opening the case and without allowing any of the cold air therein to escape, and which will effectively insulate those packages which are on display and within reach of the customer.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a perspective view illustrating an improved frozen food package as employed in this invention;

Fig. 2 is a cross section through the package of Fig. 1;

Fig. 3 is a similar cross section illustrating an insulating cap which may be placed on present packages to adapt them to the uses of this invention;

Fig. 4 is a fragmentary front view of a display case designed for handling the improved packages;

Fig. 5 is a detail section through the front panel of the case, taken on the line 5—5, Fig. 4; and

Fig. 6 is a vertical section therethrough, taken on the line 6—6, Fig. 4.

The improved display case may be used either with package of Figs. 1 and 2 or with standard packages containing the cap structure of Fig. 3.

The improved package comprises a box-like food carton 10 which is formed with an indentation or groove 11 completely surrounding the package immediately to the rear of the front

thereof. The cardboard sheet forming the package continues forwardly of the package to form the groove 11 and across the face thereof to form a front 12; thence, turns rearwardly to form a continuation of the groove 11 and terminates in a flap 13. The other side of this sheet is extended across the front to form a false front 14. The space between the fronts 12 and 14 forms an insulating compartment 15 over the entire front of the box.

The insulating compartment 15 is filled with any suitable insulation. As illustrated, it contains a corrugated cardboard pad 16 which forms dead air spaces therein. A finger tab 17 is cut from the front 12 to provide a finger grip thereof.

If desired, present cartons may be adapted to the use of this invention by placing a cardboard cap 18 (see Fig. 3) on the front of a standard carton, such as indicated in broken line 19. The cap 18 contains insulating compartment 20 similar to that of the previously described form. The cap is also provided with a peripheral groove 21 about the compartment 20 as in the previous form. In both forms, the food carton 10 and the standard carton 19 are thermally insulated at their front faces. The front faces 12 and the front faces of the caps 18 may carry suitable advertising of the contents of the cartons.

The above described structures are for use in a special display cabinet such as illustrated in Figs. 4, 5 and 6. This cabinet comprises a suitable enclosing cabinet which is insulated in any desired manner to exclude heat. The refrigeration may be supplied in any desired manner. As illustrated, the cabinet is cooled by means of freezing shelves 23 through which brine or other freezing liquid is circulated as is usual in refrigerator construction.

A plurality of track bars 24 are positioned over each shelf 23 for supporting rows of the cartons 10. Each row of cartons is continually urged forward on the track bars 24, between suitable guide rods 25, by means of a compression spring 26. Thus, as each carton is removed from the front of the row another carton will be forced forwardly by the spring to replace it.

The front of the cabinet 22 is closed by means of a facing 27 having a plurality of display openings, there being one opening in front of each row 50 of cartons. Each opening is framed by means of flexible strips 28 of rubber, flexible plastic, rubber impregnated fabric or any other similar material which are secured to the facing 27 by means of suitable bolts or screws 29 or in any other desired manner. The strips 28 project into the paths of

the cartons so as to engage into the peripheral grooves 11 of the cartons of Fig. 1 or the peripheral grooves 21 of the caps 18 as shown in Fig. 5.

Therefore, the foremost carton or package in each row seals the front of the cabinet and the insulated fronts of the cartons and strips 28 form the insulation over the entire front of the cabinet.

In use, the customer selects the desired carton from the many on display and grips the tab 17 thereof. By pulling on the tab he draws the desired carton from the grip of the flexible strips 28 and withdraws it from the cabinet. The spring now acts to force the next succeeding carton forwardly into the flexible frame formed by the strips 28 immediately sealing the refrigerated cabinet. If the caps 18 are employed, the customer removes the cap from the carton and leaves it in a suitable container for reuse on other packages. If the carton 10 is used the entire carton with its insulated front is carried away with the food.

If desired, additional flexible sealing strips such as indicated at 30 (Fig. 5) may be employed for insuring a seal about the cartons at the front of the cabinet. It is preferred to make the front portions of the cartons and caps, that is, the portions extending forwardly from the groove 11 on the carton, indicated at 31, and the portion extending forwardly from the groove 21 of the cap, indicated at 32, slightly smaller than the remaining portions of the cartons themselves. This causes the grooves 11 and 21 to have a lower wall on the side toward the front than on the side at the rear so that the springs will be enabled to force the fronts past the sealing strips 28 without forcing the entire carton past the strips. This assures the carton stopping at the proper point for the sealing strips to engage in the grooves 11 and 21.

It will be noted that the strength of the springs diminishes as they become extended but it will also be noted that the springs have less carton weight to move as they become extended so the resultant push on the foremost package is equalized at all times.

This invention is designed more particularly as an improvement over the construction shown in applicant's prior Patent No. 2,299,347.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. Means for storing frozen foods comprising a cabinet; means for refrigerating said cabinet; track members in said cabinet for supporting rows of cartons therein, said cabinet having openings in its front one in front of each row to allow the cartons to pass therethrough; and a flexible sealing member framing each opening; and means for forcing the rows of cartons forwardly so that the foremost carton of each row will contact said

sealing member to seal said cabinet, each of said cartons being provided with a peripheral recess adjacent the front face for receiving the edges defining the opening of one of the sealing members.

2. Means for storing frozen foods comprising: a cabinet; means for cooling the interior of said cabinet; a plurality of stationary, horizontal track members in said cabinet for supporting a plurality of rows of front to rear cartons therein, said track members terminating at the front wall of said cabinet, there being an opening in said front wall in alignment with each row of cartons, said openings being larger than said cartons to allow the latter to pass therethrough; a flexible sealing frame surrounding each opening and reducing the size of the opening to less than the size of the carton; means for forcing the rows of cartons forwardly so that the foremost carton of each row will contact said sealing frame to seal said cabinet; and a heat insulated front on the forward side of each carton to insulate the opening in said sealing frame.

3. Means for storing frozen foods comprising: a cabinet; means for cooling the interior of said cabinet; a plurality of stationary, horizontal track members in said cabinet for supporting a plurality of rows of front to rear cartons therein, said track members terminating at the front wall of said cabinet, there being an opening in said front wall in alignment with each row of cartons, said openings being larger than said cartons to allow the latter to pass therethrough; a flexible sealing frame surrounding each opening and reducing the size of the opening to less than the size of the carton; means for forcing the rows of cartons forwardly so that the foremost carton of each row will contact said sealing frame to seal said cabinet; and a heat insulated front wall on the forward side of each carton to insulate the opening in said sealing frame, said wall being smaller than the remaining portion of said carton so that the front wall may pass through the sealing frame, with the latter retaining the carton in place.
